(57) CLAIM

The ornamental design for a cart, as shown and described.

DESCRIPTION

FIG. 1 is a perspective view of a cart showing my new design;
FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view with two layers.

The broken line portions of the cart in FIGS. 1-8 represent unclaimed portions of the claimed design and form no part thereof. The dot-dash broken lines in FIGS. 1-5 and 8 represent unclaimed boundary lines and form no part of the claimed design.

1 Claim, 7 Drawing Sheets
